UNITED STATES PATENT OFFICE.

LEON T. WYNDHAM, OF ATLANTA, GEORGIA, ASSIGNOR OF ONE-HALF TO JAC R. RARDON, OF CHARLOTTE, NORTH CAROLINA.

DESIGN FOR A REFRIGERATOR OR SIMILAR ARTICLE.

Application filed November 15, 1922. Serial No. 4,301. Term of patent 3½ years.

To all whom it may concern:

Be it known that I, LEON T. WYNDHAM, a citizen of the United States, residing at Atlanta, in the county of Fulton and State of Georgia, have invented a new, original, and ornamental Design for a Refrigerator or Similar Article, as shown in the accompanying drawing, forming part of this specification.

In the drawing, the figure shows a perspective view of a refrigerator or similar article embodying my new design.

I claim:

The ornamental design for a refrigerator or similar article substantially as shown.

LEON T. WYNDHAM.
